UNITED STATES PATENT OFFICE

143,671

DESIGN FOR AN ASH STAND

William C. Panzer, Chicago, Ill.

Application October 27, 1945, Serial No. 123,241

Term of patent 14 years

(CL D85—2)

To all whom it may concern:

Be it known that I, William C. Panzer, a citizen of the United States, residing in Chicago, Cook County, Illinois, have invented a new, original, and ornamental Design for an Ash Stand, of which the following is a specification, reference being had to the accompanying drawing, forming a part thereof.

The stippled portions represent a pebbled flat-paint surface.

I claim:

The ornamental design for an ash stand, substantially as shown and described.

WILLIAM C. PANZER.
